UNITED STATES PATENT OFFICE.

EDMUND N. BROWN, OF SAN FRANCISCO, CALIFORNIA.

DESIGN FOR AN ELECTRIC HEATER.

54,890.

Specification for Design.

Patented Apr. 20, 1920.

Application filed September 16, 1919. Serial No. 324,254. Term of patent 14 years.

To all whom it may concern:

Be it known that I, EDMUND N. BROWN, a citizen of the United States, and resident of the city and county of San Francisco, State of California, have invented a new, original, and ornamental Design for Electric Heaters, of which the following is a specification, reference being had to the accompanying drawings, forming a part thereof.

Figure 1 is a front view of my heater.

Fig. 2 is a side view of my heater.

Fig. 3 is a back view of my heater.

I claim:

The ornamental design of an electric heater substantially as shown.

EDMUND N. BROWN.
